Filed Aug. 17, 1966, Ser. No. 3,511

Term of patent 14 years

(Cl. D34—5)

FIG. 1

FIG. 2

FIG. 3

FIG. 4

FIG. 1 is an elevated view of the left side of rocket-shaped seat for playground apparatus showing my new design, the right side being identical thereto.

FIG. 2 is a plan view of my new design.

FIG. 3 is a front, elevational view of rocket-shaped seat for playground apparatus showing the new design, and

FIG. 4 is a rear, elevational view thereof.

The characteristic features of my design reside in the combination on the rocket-shaped body of the scalloped nose and the saddle portion with a pair of fins emanating from the central bottom rocket body, all as shown.

I claim:

The ornamental design for rocket-shaped seat for playground apparatus, substantially as shown and described.
